UNITED STATES PATENT OFFICE.

ROBERT M. HINMAN, OF AKRON, OHIO, ASSIGNOR TO THE STATE FOUNDRY AND PATTERN COMPANY, OF AKRON, OHIO, A CORPORATION OF OHIO.

APPARATUS FOR CASTING MOLDS OR THE LIKE.

Application filed April 21, 1926. Serial No. 103,521.

This invention relates to the art of casting iron or steel and particularly to an apparatus designed for the casting of circular molds which are used in the manufacture of inner tubes for use with pneumatic automobile tires.

It is desirable in casting molds for the vulcanization of tires or tubes, or other articles of rubber, that the metal be chilled for the reason that chilling cast metal gives it a smooth, close grain which is particularly desirable for the vulcanization of rubber. If the metal is not chilled, a porous, open surface will be formed in the metal which surface is not desirable. Attempts at polishing or finishing the surface of molds cast without chilling having not been satisfactory, as after a few curing operations the pores in the metal open up and reproduce an inferior surface in the rubber.

The present invention is for the purpose of constructing molds of special forms in which the molding cavity is formed with an overhanging portion which if cast about the usual chill may result in cracking of the casting upon cooling. The problem presented has been to construct a chill for the purposes set forth and for similar purposes. The design of chill here shown is especially adaptable for this work and enables the metal to be cast without danger of breaking the chill or the casting, and while a tube mold has been shown, the principles of the invention may be applied to other objects.

The chill here shown is a two-part chill provided with a cushioning sand core or intermediate wall between the parts, which wall permits the casting to contract without breakage. The chill is also constructed so that it can be withdrawn easily from the mold.

In the drawings, in which one form of the invention is shown:

Figure 1 is a sectional view through a mold showing the casting therein; and

Figure 2 is a plan view.

The molding apparatus comprises the usual drag 1 and cope 2 which are held in position by pins 3 passing through lugs 4 and by U-shaped clamps 5.

The casting is indicated by the numeral 10, having the cavity 11 formed therein. It will be observed that this molding cavity is substantially circular in cross-section, the outer wall of the cavity overhanging the interior thereof. The line to which the finished mold

is machined out is indicated by the numeral 12.

Attempts to form castings of this shape upon chills have been failures, prior to my invention, because of the fact that the contraction of the casting upon cooling about the chill will crack the castings, for the reason stated, this form of mold has heretofore been cast about sand cores with consequent inferior texture of the cast metal.

By the use of my invention, however, the molder is enabled to cast the metal about a chill. This is accomplished by the special design of the chill to be described.

The chill comprises a single ring-shaped chill 15 of the cross-section shown in Figure 1, the wall 16 of the chill conforming to the curvature of a portion of the interior of the casting. The remainder of the chill is formed of a sectional chill 17, the various sections and their lines of division being shown in Figure 2. These sections are bound together by a suitable tie 18 comprising a flexible cable or the like tied about the same in groove 18^a, and are spaced from the main portion of the chill by a layer or wall of cushioning material, such, for example, as sand, shown at 19.

The remainder of the mold is made up in accordance with standard foundry practices being shown, but not described.

With a chill thus constituted, castings of the form shown, or similar forms, may be made without danger of fracture upon cooling, the said layer 19 cushioning the two portions of the chill. The chill is easily removed by taking out the major or solid portion of the chill and then several parts of the sectional chill may be removed.

The principles of the invention may be utilized for the casting of other objects than that specifically shown and described, and changes and modifications may be made in embodiments of the invention as will be apparent to those skilled in the art to which this apparatus.

What is claimed is:

1. A chill for forming annular cavities in annular articles, comprising two annular portions, one of said portions being a solid chill and the other portion a sectional chill, and a layer of cushioning material between the two portions of the chill.

2. A chill for forming annular cavities in annular articles having an undercut cavity

therein, said chill comprising two annular portions, one of said portions being a solid chill and the other portion a sectional chill, and a layer of sand between the two portions 5 of the chill.

3. A chill for casting circular molds having an undercut circular cavity therein, said chill comprising a solid ring portion and a sectional ring portion, and a wall of sand lo-

cated between said portions and acting as a 10 cushion therebetween.

4. A two part chill comprising a solid ring and a sectional ring adjacent thereto, and a layer of sand between the parts of the chill 15 to cushion said parts and permit radial contraction of the casting without breaking.

ROBERT M. HINMAN.
